MATRIX RETAINER

Orin C. Samphire, West Allis, Wis.

Application January 11, 1943, Serial No. 472,009

6 Claims. (Cl. 32—63)

The present invention relates generally to improvements in the art of dentistry, and relates more specifically to improvements in the construction and operation of dental instruments of the type known to the profession as matrix retainers.

An object of this invention is to provide an improved matrix ribbon clamp and retainer which is simple and compact in construction, and which is moreover highly efficient in use.

It has long been common practice in the art of dentistry, to fill cavities in teeth by first properly preparing each cavity, thereafter snugly surrounding the tooth and cavity with a flexible metallic strip known as a matrix ribbon, then inserting the filling or impression wax, and by finally removing the matrix ribbon and finishing the filling. These matrix ribbons are highly flexible in order to cause them to readily conform with the contour of the teeth embraced thereby, and were ordinarily clamped about the selected teeth with the aid of a matrix retainer having a screw adjustment for producing the desired clamping action. While these prior matrix retainers are quite effective when applying and clamping a flexible ribbon about a cylindrical body having a recess in the side thereof, they are not well adapted to cause such a ribbon to snugly embrace a tapered object such as a molar or bicuspid tooth; and when the ordinary matrix retainer is used on such an inherently tapered tooth it invariably leaves an open crevice or gap near the tooth root and adjoining the cavity, through which material may escape when packed into the cavity and which also produces a shoulder or off-set at the bottom of the final filling. While some attempts at avoiding such crevices or gaps by utilizing specially shaped matrix ribbons, have heretofore been made, these prior efforts have not only been tedious but have also been relatively unsatisfactory especially when used on the molars which usually taper abruptly toward the roots and are also comparatively inaccessible for application of these special matrix strips. The prior matrix ribbon retainers moreover could not be readily dismantled for inspection and cleaning, and were therefore rather unsanitary in use.

The present invention therefore contemplates the provision of an improved clamp and retainer whereby flexible matrix ribbons or the like may be quickly and effectively applied to even the most abruptly tapered teeth, so as to avoid shoulders or off-sets at the edges of fillings and to provide smooth contours for the filled teeth.

Another specific object of this invention is to provide an improved matrix ribbon clamping device which is adapted for either manual or automatic adjustment so as to cause an ordinary matrix strip to properly coat with irregular and tapered teeth at all edges of lateral relatively inaccessible cavities therein.

A further specific object of my invention is to provide a new and extremely useful and efficient matrix retainer, which can be quickly dismantled for inspection and cleaning, and thereafter readily reassembled, and which may therefore be kept in highly sanitary condition.

Still another specific object of the invention is to provide a durable and readily manipulable matrix ribbon clamp and retaining implement, which may be manufactured and sold at moderate cost and which is also flexible in its adaptations.

20 These and other specific objects and advantages of the present improvement will be apparent from the following detailed description.

A clear conception of the several features constituting the present invention and of the mode 25 of constructing and of manipulating one of the improved matrix retainers, may be had by referring to the drawing accompanying and forming a part of this specification wherein like reference characters designate the same or similar 30 parts in the various views.

Fig. 1 is a part sectional top view of several normal teeth of a lower jaw, showing one of the improved matrix retainers partially in section, cooperating with a matrix ribbon applied to one 35 of the bicuspid; parts;

Fig. 2 is an inside elevation of the assemblage of Fig. 1;

Fig. 3 is an outside elevation of the assemblage of Figs. 1 and 2;

40 Fig. 4 is an enlarged fragmentary central longitudinal section through one of the improved matrix retainers;

Fig. 5 is a similarly enlarged fragmentary inner side view of the ribbon carrying end of the 45 instrument, showing the adjustable ribbon guides disposed at an extreme angle relative to each other; and

Fig. 6 is a longitudinal central section through 50 one of the improved devices, showing the mode of assembling and dismantling for cleaning purposes.

While the invention has been shown herein as having been specifically embodied in a somewhat improved type of dental matrix retainer especially adapted to cooperate with highly flexible

and readily distortable metallic matrix ribbon, it is not my desire or intent to unnecessarily restrict the scope or the utility of the improvement by virtue of such specific embodiment.

Referring to the drawing, the improved matrix retainer shown therein comprises in general a one-piece elongated sheet-metal frame 8 having an opening or transverse slot 9 near one end, an integral bifurcated wall 10 at its opposite end, and guideways 11 extending therealong between the slot 9 and end wall 10; an elongated sheet-metal slide 12 coacting with the guideways 11 of the frame 8 and having a rigid ribbon clamping abutment 13 at one end, and an integral wall 14 at its opposite end provided with a threaded opening 15; an elongated threaded clamping rod 16 having one end cooperable with the slide abutment 13 to firmly clamp the ends of a piece of matrix ribbon 17 thereagainst, while its opposite end is provided with a manipulating knob or handle 18, and its medial screw-threaded portion coacts with the threaded slide opening 15; an adjusting nut 19 for the slide 12, coacting with the screw threads of the rod 16 and having a reduced circular portion or annular groove 20 normally journaled in the bifurcation 21 of the frame wall 10; and a pair of angularly adjustable ribbon guides 22, 23 which are swingably adjustably suspended from the frame 8 near the slot 9 by means of pivot screws 24, 25 respectively.

The frame 8 and slide 12 may be formed of suitable sheet material, preferably metal, with the aid of punches and dies, and the opposite sides of the elongated frame 8 are provided with integral flanges 26 portions of which are bent inwardly toward each other to form the guideways 11. The slide 12 is movable between these side flanges 26 and along the guideways 11 by the nut 19 coacting with the screw threads of the rod 16 and which is journaled for rotation in the bifurcation 21 of the frame end wall 10; and while the threaded rod 16 has screw thread coaction with the opening 15 of the slide wall 14, it has no such screw thread coaction with the abutment or clamping end of the slide 12 but is merely freely rotatable within the opening 27 of the slide as shown in Fig. 4.

The threaded clamping and adjusting rod 16 is preferably of sufficient length, so that continued rotation of the ribbon tensioning nut 19 in the proper direction, will ultimately cause the slide 12 to leave the free end of the guideways 11 as in Fig. 6, whereupon the nut 19 may be freely removed from the bifurcation 21 and the rod and slide assemblage may be removed from the frame 8. The rod 16 may also be readily removed from the slide 12 and nut 19, by merely rotating the rod 16 relative to these parts with the aid of the handle 18, thus permitting thorough cleansing and sterilization of all parts, and the elements may obviously be readily reassembled in an obvious manner.

The matrix strip or flexible ribbon 17 is ordinarily formed of thin metal and may be of any predetermined or selected length dependent upon the size of the tooth 28 having a cavity 29 therein which is to be filled, and the ends of the ribbon pass through the opening or slot 9 in the frame 8 and may be firmly clamped against the slide abutment 13 as illustrated in Figs. 1 and 4. The ribbon 17 passes between the adjustable guides 22, 23 and is adapted to coact with curved flanges 30 formed integral with these guides so as to eliminate sharp bends; and the two guides

22, 23 are independently pivotally adjustable about their respective retaining screws 24, 25. These screws 24, 25 may be utilized to either fixedly position the guides 22, 23 in any desired angular position as shown in Fig. 5, or they may be left loose enough so that the guides will automatically assume various angular positions, but in either case they will by proper setting cause the loop of the ribbon 17 to snugly coact with objects such as teeth 28 having different tapers or contours.

The improved matrix retainer is applicable to any of the molars or bicuspids of either jaw, and has been shown applied to one of the bicuspids in Figs. 1 to 3 inclusive. During normal use of the instrument, the dentist should first prepare the cavity 29 for reception of the filling and should select a piece of matrix ribbon 17 of sufficient length to embrace the tooth 28 which is to be filled. The ends of the flexible ribbon 17 may then be inserted through the frame slot 9 while the slide abutment 13 is disposed adjacent to this slot, and the extreme ends of the ribbon can then be firmly clamped to the abutment by rotating the clamping rod 16 within the opening 15 of the wall 14. After this clamping of the ribbon ends has been effected, the nut 19 may be rotated to move the slide 12 along the guideways 11 toward the frame end wall 10 and away from the opening or slot 9, thereby diminishing the size of the ribbon loop. The pivot screws 24, 25 for the guides 22, 23 may then be loosened to permit pivotal swinging of these guides, and these screws may either be left in loosened condition so as to permit automatic shifting of the guides 22, 23, or they may be tightened after the guides have been set to conform with the taper of the tooth 28 which is to be treated, so as to hold the ribbon guiding flanges 30 in fixed position.

The loop of the ribbon 17 may then be slipped over the tooth 28 to a position closely adjoining the gum 31, whereupon the nut 19 should be rotated so as to shift the slide 12 away from the slot 9. This adjustment of the slide 12 will cause the ribbon loop to be drawn snugly about the tooth 28 and cavity 29, and the guide flanges 30 will effectively cause the flexible ribbon 17 to hug the tapered exterior of the tooth and to thoroughly seal the bottom of the cavity 29 regardless of the shape or degree of taper of the tooth 28. The filling material or impression wax may then be inserted within the cavity 29 and will be prevented by the ribbon 17 from extension beyond the tapered side of the tooth 28, and after the inserted material or wax has set, the nut 19 may again be manipulated to move the slide 12 away from the frame wall 10 and toward the slot 9, thereby releasing the ribbon tension and enlarging the loop of the ribbon 17 sufficiently to permit free withdrawal thereof from the tooth 28.

After a tooth 28 has been thus filled with the aid of the improved device, the slide 12 may again be positioned with the abutment 13 thereof over the slot 9, and the screw 16 may be rotated relative to the slide wall 14 and opening 15 so as to release the ribbon ends. The used ribbon 17 may then be removed, whereupon the slide 12 and rod 16 together with the nut 19, may be completely removed from the frame 8 as shown in Fig. 6, for cleaning and sterilization. When cleansing has been effected, the parts may be quickly and readily reassembled so as to place the implement in condition for subsequent use,

and the entire manipulation is obviously very simple.

From the foregoing detailed description of the construction and operation of the improved matrix retainer, it will be apparent that the present invention provides an implement which will permit rapid and effective application of a flexible matrix ribbon to even the most abruptly tapered teeth, in a manner which will avoid shoulders or off-sets at the edges of the cavities and fillings. The improved matrix ribbon clamping device is obviously adapted for either manual or automatic adjustment of the guides 22, 23 so as to cause the flexible matrix strip or ribbon 17 to properly coat with the irregular and tapered bodies of the teeth 28 at all edges of the cavities 29. The improved implement may moreover be conveniently and quickly dismantled for cleaning purposes, and may be just as quickly reassembled for subsequent use, and the several parts of the improved ribbon clamp and retainer may obviously be manufactured from relatively inexpensive materials and with the aid of simple equipment. My improved matrix retainer has proven highly satisfactory in actual use, and can be manipulated by inexperienced persons so as to produce most effective results with minimum loss of time.

It should be understood that it is not desired to limit this invention to the exact details of construction or to the precise mode of use of the specific device herein shown and described, for various modifications within the scope of the appended claims may occur to persons skilled in the art.

I claim:

1. In combination, an elongated frame having a transverse slot, a slide movable along said frame, a rod extending along said frame and coacting with said slide and being adapted to clamp the ends of a flexible ribbon to the slide so as to form a tooth embracing loop adjacent to the frame and extending outwardly through said slot, adjusting means coacting with said rod and frame for moving said slide to vary the size of said loop, and a pair of movable ribbon guides carried by said frame on opposite sides of said slot and coacting with the ends of the loop, said guides being relatively angularly adjustable to cause said loop to assume a taper conforming with the taper of the tooth to which the loop is snugly applied.

2. In combination, a frame having a transverse slot, a slide movable relative to said frame, a threaded rod coacting with said slide and being adapted to clamp the ends of a flexible ribbon to the slide so as to form a loop extending laterally from said frame and outwardly through said slot, a nut journaled in said frame and coacting with the screw threads of said rod to move said slide relative to said frame, and automatically adjustable guides swingably suspended from said frame on opposite sides of said slot and coacting with

the ends of the loop to cause said loop to assume a definite laterally tapered formation when the same is drawn into snug engagement with a tapered tooth.

5 3. In combination, a frame having a transverse slot, means carried by said frame and being adapted to clamp the ends of a piece of flexible ribbon to form a tooth embracing loop disposed near an end of the frame and extending outwardly through said slot, adjusting means coacting with said frame to vary the size of said loop, and a pair of spaced and freely relatively angularly adjustable guides carried by said frame on opposite sides of said slot and coacting with said ribbon between its clamped ends and said loop for causing the ribbon loop to assume a definite laterally tapered formation when the loop is drawn into snug embracing engagement with a tapered tooth.

10 4. In combination, an elongated frame having a transverse slot near one end thereof, a slide movable along said frame and away from said slot, a rod coacting with said slide and being operable to clamp a flexible ribbon to the slide so as to form a loop extending outwardly through said slot, means coacting with said frame and rod to move said slide away from said slot, and a guide pivotally suspended from said frame on each side of said slot, said guides coacting with said ribbon and being relatively angularly adjustable to

15 cause the ribbon loop to assume the taper of the tooth to which the loop is snugly applied.

20 5. In combination, an elongated frame having a transverse slot near one end and guideways extending away from said slot, a slide movable along said guideways, a rod coacting with said slide and being operable to clamp a flexible ribbon to the slide so as to form a loop extending outwardly through said slot, means coacting with said frame and rod to move said slide along said guideways away from said slot and to thereby diminish said loop, and a guide swingably suspended from said frame on each side of said slot and coacting with the adjacent end of the loop, said guides being relatively angularly displaceable to

25 cause the loop to assume the taper of the tooth about which the loop is snugly drawn when said slide is moved away from said slot.

30 6. In combination, a frame having a transverse slot, a slide movable along said frame, a rod coacting with said frame and slide to move the latter relative to said slot, means for fastening a matrix ribbon to said rod and slide to form a loop extending outwardly through said slot, means for moving said rod to diminish the size of said loop, and a guide pivotally attached to said frame on each side of said slot and coacting with the adjacent end of the loop, said guides being relatively angularly displaceable to cause the loop ribbon to snugly embrace teeth of diverse tapered formations.

35 7. In combination, an elongated frame having a transverse slot near one end and guideways extending away from said slot, a slide movable along said guideways, a rod coacting with said slide and being operable to clamp a flexible ribbon to the slide so as to form a loop extending outwardly through said slot, means coacting with said frame and rod to move said slide along said guideways away from said slot and to thereby diminish said loop, and a guide swingably suspended from said frame on each side of said slot and coacting with the adjacent end of the loop, said guides being relatively angularly displaceable to

40 cause the loop to assume the taper of the tooth about which the loop is snugly drawn when said slide is moved away from said slot.

45 8. In combination, an elongated frame having a transverse slot, a slide movable along said frame, a rod coacting with said slide and being operable to clamp a flexible ribbon to the slide so as to form a loop extending outwardly through said slot, means coacting with said frame and rod to move said slide along said guideways away from said slot and to thereby diminish said loop, and a guide swingably suspended from said frame on each side of said slot and coacting with the adjacent end of the loop, said guides being relatively angularly displaceable to cause the loop to assume the taper of the tooth to which the loop is snugly applied.

50 9. In combination, a frame having a transverse slot, a slide movable along said frame, a rod coacting with said slide and being operable to clamp a flexible ribbon to the slide so as to form a loop extending outwardly through said slot, means coacting with said frame and rod to move said slide along said guideways away from said slot and to thereby diminish said loop, and a guide swingably suspended from said frame on each side of said slot and coacting with the adjacent end of the loop, said guides being relatively angularly displaceable to cause the loop to assume the taper of the tooth to which the loop is snugly applied.

55 10. In combination, a frame having a transverse slot, a slide movable along said frame, a rod coacting with said slide and being operable to clamp a flexible ribbon to the slide so as to form a loop extending outwardly through said slot, means coacting with said frame and rod to move said slide along said guideways away from said slot and to thereby diminish said loop, and a guide swingably suspended from said frame on each side of said slot and coacting with the adjacent end of the loop, said guides being relatively angularly displaceable to cause the loop to assume the taper of the tooth to which the loop is snugly applied.

60 11. In combination, a frame having a transverse slot, a slide movable along said frame, a rod coacting with said slide and being operable to clamp a flexible ribbon to the slide so as to form a loop extending outwardly through said slot, means coacting with said frame and rod to move said slide along said guideways away from said slot and to thereby diminish said loop, and a guide swingably suspended from said frame on each side of said slot and coacting with the adjacent end of the loop, said guides being relatively angularly displaceable to cause the loop to assume the taper of the tooth to which the loop is snugly applied.
